UNITED STATES PATENT OFFICE.

HARRIS NEWTON SUMMER, OF CASCADE, MARYLAND.

DESIGN FOR A CANDY EASTER EGG.

Application filed December 22, 1922. Serial No. 4,679. Term of patent 7 years.

To all whom it may concern:

Be it known that I, HARRIS NEWTON SUMMER, a citizen of the United States, and a resident of Cascade, in the county of Washington and State of Maryland, have invented a new, original, and ornamental Design for Candy Easter Eggs, of which the following is a specification, reference being

had to the accompanying drawing, forming part thereof.

The figure is a front view of a candy Easter egg showing my new design.

I claim—

The ornamental design for a candy Easter egg as shown.

HARRIS NEWTON SUMMER.
